WINGED DWELLING STRUCTURE

William H. Buck-Pitt, 1831 E. Hayden Lane,
Tempe, Ariz. 85281

Filed June 8, 1973, Ser. No. 368,235

Term of patent 14 years

Int. Cl. D25—03

U.S. Cl. D13—1 A

fig. 1

fig. 2

fig. 3

fig. 4

FIG. 1 is a perspective view of the winged dwelling structure of my present invention generally showing the details and features of my new design;

FIG. 2 is an end view taken along lines 2—2 of FIG. 1 of the winged dwelling structure of my present invention generally showing the details and features of my new design;

FIG. 3 is a top view of the winged dwelling structure of my present invention generally showing the details and features of my new design; and

FIG. 4 is a side view taken along lines 4—4 as shown in FIG. 2 of the winged dwelling structure of my present

invention generally showing the details and features of my new design.

I claim:

The ornamental design for a winged dwelling structure, as shown.
